UNITED STATES PATENT OFFICE.

HENRY TIDEMAN, OF MENOMINEE, MICHIGAN.

DESIGN FOR A TABLE-FAN.

46,781.

Specification for Design.

Patented Dec. 15, 1914.

Application filed July 9, 1914. Serial No. 850,021. Term of patent 7 years.

To all whom it may concern:

Be it known that I, HENRY TIDEMAN, a citizen of the United States, residing at Menominee, in the county of Menominee and State of Michigan, have invented a new, original, and ornamental Design for a Table-Fan, of which the following is a specification, reference being had to the accompanying drawing, forming part thereof.

The figure is a view in elevation of a table fan, showing my new design.

The characteristic features of my new

design are its symmetrical appearance in general when viewed from any angle, and its ornamental goblet-like appearance which is well adapted to match and conform with the usual scheme of table decoration.

I claim:

The ornamental design for a table fan, as shown and described.

HENRY TIDEMAN.
